(57) **CLAIM**

The ornamental design of an electric actuator, as shown and described.

DESCRIPTION

The file of this patent contains at least one photograph executed in color. Copies of this patent with color photographs will be provided by the Office upon request and payment of the necessary fee.

FIG. 1 is a front view of an electric actuator as showing my new design, with the rear view being substantially a mirror image thereof, the sole difference being with regards to the visible portions of the elements on the right side of the design;

FIG. 2 is a right side elevational view thereof;

FIG. 3 is a left side elevational view thereof;

FIG. 4 is a top plan view thereof;

FIG. 5 is a bottom view thereof;

FIG. 6 is a perspective view thereof; and,

FIG. 7 is another perspective view thereof.

The broken lines show portions of an electric actuator that form no part of the claimed design.
